CLAIM

The ornamental design for a vehicle front fascia, as shown and described.

DESCRIPTION

FIG. 1 is a perspective view of the vehicle front fascia; FIG. 2 is a front view thereof;

FIG. 3 is a left side view thereof (where the right side view is substantially a mirror image of the left side view);

FIG. 4 is a top view thereof; and,

FIG. 5 is a bottom view thereof.

The broken lines shown in the drawings depict portions of the vehicle front fascia that form no part of the claimed design.
